2,318,761

SHIELDED AMPLIFIER REVERSING SWITCH

Roger C. Curtis, New Haven, Conn., assignor to
 Dictaphone Corporation, New York, N. Y., a
 corporation of New York

Application December 27, 1941, Serial No. 424,578

13 Claims. (Cl. 200—1)

This invention relates to switching apparatus, and more particularly to such apparatus intended for use in interconnecting high impedance alternating current circuits.

In performing switching operations in alternating current circuits, and especially in high impedance circuits, it is usually disadvantageous, if not impossible, to use the switching arrangements customarily employed in D. C. or low-frequency, low-impedance A. C. circuits because of the effect of the capacity between the various contact elements of the switching arrangements. This intercontact capacity is usually of sufficient value to cause a transfer of A. C. energy between contact elements of the switch, even though the contact elements are not physically connected.

It is an object of this invention to provide a simple and inexpensive switching arrangement in which the detrimental effect of such intercontact capacity is eliminated.

In electric dictating machines the problem of providing a suitable switching arrangement for interconnecting various audi-frequency circuits is a particularly difficult one. In such machines, for example, it is customary to provide a single translating unit used both as a recording microphone and as a reproducing loudspeaker, a single amplifier unit, and a single translating unit cooperating with a record to act both as a recording head and as a reproducing pickup. When such a machine is adjusted for recording, the microphone unit is connected to the input of the amplifier and the recording head is connected to the output of the amplifier. When the machine is conditioned for reproducing the amplifier connections are reversed, the microphone unit is disconnected from the input of the amplifier and connected to the amplifier output to act as a loudspeaker, and the recording head is disconnected from the output of the amplifier and connected to the amplifier input to act as a phonograph pickup. To be commercially practical such a machine must be arranged so that this amplifier reversal can be accomplished by a simple switching operation. If only direct currents or low-frequency low-impedance alternating currents were involved this switching operation could be accomplished by providing an ordinary double-pole double-throw switch to reverse the connections of the amplifier. However, due to intercontact capacity effects, a simple D. C. switching arrangement cannot be used for high gain audio-frequency circuits of the type required in such a machine because of the danger

of feedback in the amplifier. The input and the output circuits of the amplifier both must be connected to contact points in the switch structure, and, even though all of the connecting circuits are carefully protected by grounded shields, there is ordinarily sufficient capacity between these contact points to produce a feedback phenomenon in the amplifier by electrically interconnecting the input and output circuits. The difficulties of this situation are even further enhanced if high impedance translating devices, such, for example, as piezo-electric crystal devices, are used in the microphone-loudspeaker and the recorder-reproducer units.

Accordingly, therefore, it is a further object of this invention to provide in an electric dictating machine a simple and inexpensive low-capacity switching arrangement for effectively reversing the amplifier connections when the machine is changed from recording to reproducing condition, and vice versa.

These and other apparent objects and advantages of this invention are attained by the novel structure described in the following specification which may be more readily understood by reference to the accompanying drawing in which:

Figure 1 is a schematic wiring diagram of the audi-frequency circuits of an electric dictating machine incorporating a switching arrangement in accordance with the invention;

Figure 2 is a side-elevation of a switching structure of the type shown diagrammatically in Figure 1, with a portion of the shielding casing cut away to show the construction of the switching elements;

Figure 3 is an end-elevation of the terminal portion of the switching structure shown in Figure 2; and

Figure 4 is a top plan view of the switching structure shown in Figures 2 and 3 with part of the shielding casing shown broken away.

Referring to Figure 1, a preferred embodiment of the invention is shown, in more or less diagrammatic form for convenience in illustration and description, incorporated in an electrical dictating machine of the type described, for example, in U. S. Patent No. 2,143,819 to Leland D. Norton. The mechanical structure of such a dictating machine is described in the Norton patent and details of its construction are not necessary for a complete understanding of the present invention. A dictating machine of this type for both recording and reproducing speech

essentially comprises a microphone unit 12, which also serves as a loudspeaker when reproducing, a suitable amplifier 14, a translating unit 16 capable of being selectively conditioned for recording or reproducing by means of a shift lever 15 and slidably mounted to traverse a record 18 driven by suitable driving means (not shown), and an amplifier reversing switch, generally indicated at 20, for interchanging the connections of the amplifier for dictation or listening-back. The combination microphone-loudspeaker unit 12 and the combination recorder-reproducer translating unit 16 may be any suitable type of translating devices capable of such double-purpose operation, such, for example, as the piezo-electric crystal devices shown in the above-mentioned Norton patent. The switch mechanism 20 may be operated manually by control member 24, or it may be operated by a mechanical interconnection with the shift lever 15 mounted on the translating unit 16. In Figure 1 such a mechanical interconnection is shown diagrammatically. A "dictate-listen" shift lever 26, suitably mounted on the dictating machine, is connected by a member 28 to the switch control member 24 and by another member 30 to the "record-reproduce" conditioning lever 15 of the recorder-reproducer translating unit 16. A suitable mechanical arrangement for accomplishing this mechanical interconnection, which per se forms no part of the invention herein described, is shown in the above-mentioned U. S. Patent 2,143,819 to Norton.

The amplifier switch 20 is essentially a double-pole, double-throw switch, cross-connected to act as a reversing switch. It is connected to one side of the microphone-loudspeaker unit 12, the input and output circuits of amplifier 14, and the translating unit 16 to connect the microphone-loudspeaker unit 12 to the input of the amplifier 14 and the output of the amplifier to the recorder-reproducer unit 16 when the machine is conditioned for dictating, and to reverse the amplifier connections so that its input is connected to the recorder-reproducer device 16 and its output is connected to the microphone-loudspeaker unit 12 when the machine is conditioned for listening-back. The other terminals of the microphone-loudspeaker unit 12, the amplifier input and output circuits, and the recorder-reproducer unit 16 are connected to an electrically grounded circuit 22, common to all of the apparatus. A switch structure such as would ordinarily be proposed for accomplishing such a reversing effect is shown in the above-mentioned Norton Patent 2,143,819. However, such a standard switching arrangement, especially when used to interchange the high impedance input and output terminations of an amplifier of the type designed for efficient operation with high impedance translating devices such as piezo-electric crystals, has the disadvantage that its contacts, certain of which necessarily must be connected to the input and output circuits of the amplifier, must be so disposed as to be in capacitive relation to each other, thus capacitively coupling the amplifier input and output. Such capacitive coupling between the input and output of an amplifier permits energy feedback which causes the amplifier to oscillate and renders it inoperative.

In accordance with the present invention, a simple and inexpensive switch mechanism is provided for accomplishing this amplifier reversal which has an extremely low capacity between the various contacting elements of the switch

structure due to the provision of an arrangement which automatically interposes electrically grounded shielding elements between the contacts of the switch when the contacts are open-circuited. Referring to Figures 2, 3, and 4, this simple and novel shielded reversing switch arrangement 20 includes two identical switching units, generally indicated at 34 and 36. Each of these switching units 34 and 36, comprises a stack 10 of seven leaf-spring contact members 2, 4, 6, 1, 7, 5, and 3 of varying lengths suitably arranged in the order stated in parallel relationship in a usual switch-stack construction, insulated from each other by insulated spacing members 38 and 15 clamped together and to a supporting bracket 40 by bolts 42.

As shown in the drawing, each switch stack is arranged so that the central operating leaf-spring member 1, the longest of the contact springs, is 20 adapted to be selectively positioned in a left-hand or right-hand position by the control member 24. This spring 1 carries a double-faced contact member 101, projecting on either side of the spring, which is moved into contact with contact 25 points 104 or 105 mounted on the free ends of springs 4 and 5, respectively, as operating spring 1 is moved to one or the other of its alternate positions. Leaf springs 2 and 6, and 7 and 3, all slightly shorter than springs 4 and 5 and positioned, respectively, on either side of springs 4 and 5, respectively carry contacts 102, 106, 107, and 103 on their free ends. Thus, as shown in the drawings, contacts 102 and 106 alternately contact spring 4 and contacts 107 and 103 alternately contact spring 5 as operating spring 1 is 35 moved to one or the other of its alternate positions. Leaf-spring contact members 4 and 5 are normally biased inwardly toward operating spring 1 so that they are normally in contact with 40 contact points 106 and 107, respectively. The structure of switch stack 36, comprising leaf-spring contact members 2', 4', 6', 1', 7', 5', and 3' arranged in that order, is identical with that of stack 34.

45 The two switch stacks 34 and 36 are each surrounded by electro-static shielding casings 44 and 46 (shown in dotted lines in Figure 1), provided with apertures 48 and 50, respectively, to admit the control member 24 to move the operating springs 1 and 1'. These shielding members 44 and 46 are provided with tabs 52 and 54 extending between the sets of connection lugs on the ends of each of the switch stacks, as shown in Figure 4, so as to provide a shield between the 55 connection terminals of the two switching units 34 and 36.

In the embodiment of the invention herein described, connections to switching arrangement 20 are made as shown in Figure 1. Contact 1 of switch element 34 is connected to one side of the amplifier input and contact 1' of element 36 is connected to one side of the amplifier output. Contact 2 is connected to one side of the microphone-loudspeaker unit 12 and to contact 3'. Contact 2' is connected to one side of the recorder-reproducer translation unit 16 and to contact 3. Contacts 6, 7, 6', and 7' are all connected together and to the electrically grounded circuit 22 of the apparatus, as are the shielding members 44 and 46. As above mentioned, this electrically grounded circuit 22 also forms the circuit common to the microphone-loudspeaker unit 12, the amplifier 14, and the recorder-reproducer unit 16. Contacts 4, 5, 4', and 5' have no 75 external connections and thus are connected in

the circuit only when they are in contact with other contact members.

In operation, when the shift lever 26 is moved to "dictate" position, as shown in Figure 1, leaf-spring contact member 1 is moved to its left-hand position by control member 24, bringing contact 101 in contact with contact point 104 on contact spring 4. Contact spring 4 is then moved with contact spring 1 to the left, moving spring 4 out of contact with contact point 106 and into contact with contact point 102 on contact spring 2. This connects microphone-loudspeaker unit 12 to the input of amplifier 14. In a similar manner contact spring 1' is moved to the left, making a connection with contact 4' and moving contact 4' out of contact with contact 6' and into contact with contact 2', thus connecting the output of amplifier 14 to the recorder-reproducer unit 16. This motion of contact springs 1 and 1' to the left to connect amplifier 14 in the circuit in the proper direction for recording, also permits contact springs 5 and 5' to assume their normal positions in contact with contact points 107 and 107' on contact springs 7 and 7', respectively. This connects contact springs 5 and 5' to ground and thus serves to automatically interpose shielding elements, in the form of springs 5 and 5', between contact springs 3 and 4, and 3' and 4', respectively. Thus the input and the output circuits of amplifier 14 are automatically shielded from each other, insofar as the switch contacts are concerned, thereby preventing feedback therebetween which would cause oscillations in the amplifier. In accordance with usual practice all of the connections to the microphone-loudspeaker unit 12, recorder-reproducer unit 16, and amplifier 14 are preferably made with shielded cable whose outer sheath is connected to the electrically grounded circuit 22.

Similarly, when shift lever 26 is moved to "listen" position, control springs 1 and 1' are moved to their right-hand positions, connecting the recorder-reproducer unit 16 through contacts 3, 5, and 1 to the input of amplifier 14, and connecting the output of the amplifier through contacts 1', 5', and 3' to the microphone-loudspeaker unit 12; while simultaneously contacts 4 and 4' move to their normal positions in contact with grounded contacts 6 and 6' to automatically interpose themselves as shields between contacts 2 and 1, and 2' and 1', respectively, thereby to shield the amplifier input circuit from the amplifier output circuit as above described.

In order to enhance the shielding effect of contact members 4, 5, 4', and 5', they are preferably made of wider strip material than the remaining contact springs, as shown in the broken-away portion of Figure 4, so that they completely blanket the outer contacts 2, 3, 2' and 3', respectively, and nearly touch the sides of the enclosing shielding casings 44 and 46.

The inter-circuit capacity of a switching structure, made in accordance with the present invention, can be further reduced by suitable disposition of the connection terminals attached to each of the leaf-spring contacts. Referring to Figures 2, 3, and 4, connection terminals or lugs 201 and 201' forming portions of control springs 1 and 1', the center elements of the switching units 34 and 36, respectively, are brought out from the sides of the switch-stack structures at points near the contact ends of these structures, as may be most easily seen in Figure 4. Connection terminals 202, 203, 202', and 203', forming parts of contact springs 2, 3, 2', and 3', respectively, the outside

elements of these switch units are brought out from the ends of the switch-stack structures at points as far removed as possible from connection terminals 201, and 201', see Figure 4. Further, 5 contact terminals 244 and 245 connected to the shielding casing 44, connection terminals 246 and 247 connected to the shielding casing 46, and connection terminals 206, 207, 206', and 207' projecting, respectively, from leaf-spring contacts 6, 7, 6', and 7', all of which are connected to the common electrically grounded circuit 22 (as indicated in the dotted lines of Figures 3 and 4), are brought out from the sides of the switch-stack structures at points intermediate to the positions 10 of connection terminals 201 and 201', and connection terminals 202, 203, 202', and 203'. This disposition of the various connection terminals of the switching structures herein described, places all of the electrically grounded contacts of 15 the switching structures between the electrically "high" connection terminals and thus these grounded connection terminals act as effective electro-static shields therebetween. To further aid this shielding effect, it is also desirable to extend electrically-grounded leaf springs 6, 7, 6', and 7' beyond the clamped portion of the stack so that they project between connection terminals 202 and 203, and 202' and 203', respectively, so as to shield the connections made to 20 those terminals.

It is apparent that a simple self-shielding switching arrangement, made in accordance with the present invention, is not limited to use in an electrical dictating machine and that it can be advantageously used in any electrical switching system in which it is necessary to interconnect various alternating current circuits, especially if such alternating current circuits are high impedance circuits carrying high frequency currents.

As many possible embodiments of the present invention may be made without departing from the scope thereof, it is to be understood that all matter set forth or shown in the accompanying drawing is to be interpreted as illustrative only and not in a limiting sense.

I claim:

1. A self-shielding switch structure, comprising, in combination, first contact means, second contact means, conductive means associated with said contact means to open and close a circuit therebetween, said conductive means adapted in its open-circuit position to be interposed as a shield between said contact means, and means connecting said conductive means to ground when in its open-circuit position.

2. A self-shielding switch structure, comprising, in combination, first contact means, second contact means positioned adjacent said first contact means but spaced therefrom, conductive means associated with said contact means movable to bridge the gap therebetween to open and close a circuit, and grounded means, said conductive means being movable out of said bridging position to a position between said contact means and in contact with said grounded means to act as a shield between said contact means when said circuit is open.

3. A self-shielding switching structure, comprising, in combination, first contact means, second contact means, a conductive member interposed between said contact means, control means for relatively moving second contact means selectively in one direction to close a circuit between said contact means through said conduc-

tive member and in a second direction to open said circuit and ground said conductive member, whereby said conductive member serves as a shield between said contact means when the circuit therebetween is open.

4. A shielded switching arrangement, comprising, in combination, first contact means, second contact means, conductive means interposed between said first and said second contact means, electrically grounded means adapted to contact said conductive means, mounting means movably supporting said first contact means and said conductive means for relative movement toward and away from said second contact means and said grounded means, and control means operatively associated with said first contact means and said conductive means to selectively move them in one direction relative to said second contact means and said grounded means to bring said first contact means into contact with said conductive means and to move the latter away from said grounded means into contact with said second contact means, and in a second direction to separate said first contact means, said conductive means, and said second contact means and return said conductive means to contact said grounded means, whereby said conductive means acts as a connector between said first contact means and said second contact means when said control means is operated in said first direction and as an electrically grounded shield therebetween when said control means is operated in said second direction.

5. A shielded switching arrangement, comprising, in combination, first contact means, second contact means, conductive means interposed between said first and said second contact means, electrically grounded means adapted to contact said conductive means, mounting means movably supporting said first contact means and said conductive means for relative movement toward and away from said second contact means and said grounded means, and control means operatively associated with said first contact means and said conductive means to selectively move them in one direction relative to said second contact means and said grounded means to bring said first contact means into contact with said conductive means and to move the latter away from said grounded means into contact with said second contact means, and in a second direction to separate said first contact means, said conductive means, and said second contact means and return said conductive means to contact said grounded means, whereby said conductive means acts as a connector between said first contact means and said second contact means when said control means is operated in said first direction and as an electrically grounded shield therebetween when said control means is operated in said second direction and shielding means surrounding all of said contact means and connected to said grounded means.

6. A shielded switching arrangement, comprising, in combination, a first contact, a second contact, a member of conductive material interposed between said first and said second contacts, an electrically grounded contact adjacent said conductive member and adapted to contact the latter when it is moved toward said first contact, mounting means movably supporting said first contact and said conductive member for movement toward and away from said second contact, and control means operatively associated with said first contact to selectively move it in one

direction into contact with said conductive member to move the latter away from said grounded contact into contact with said second contact, and in a second direction to separate said first contact, said conductive member, and said second contact and return said conductive member to contact with said grounded contact, whereby said conductive member acts as a connector between said first contact and said second contact when said control means is operated in said first direction and as a grounded electro-static shield therebetween when said control means is operated in said second direction.

7. A shielded switching arrangement, comprising, in combination, a first leaf spring carrying a first contact point, a second leaf spring carrying a second contact point, a conductive member in the form of a third leaf spring interposed between said first and said second springs and normally positioned out of contact therewith, a fourth leaf spring carrying an electrically grounded contact point interposed between said first spring and said conductive member and normally biased to contact the latter, insulated mounting means movably supporting said springs in parallel relationship, and control means operatively connected to said first leaf spring selectively to move said first contact point in one direction into contact with said conductive member to pick up the latter and move it away from said grounded contact point into contact with said second contact point, and in a second direction to permit said first contact point, said conductive member, and said second point contact to separate and to restore the connection between said conductive member and said grounded contact point, whereby said conductive member acts as a connector between said first contact point and said second contact point when said control means is operated in said first direction and as a grounded electro-static shield therebetween when said control means is operated in said second direction.

8. A shielded switching device, comprising, in combination, first contact means, second contact means, third contact means positioned on the opposite side of said first contact means from said second contact means, first conductive means interposed between said first and said second contact means, second conductive means interposed between said first and said third contact means, electrically grounded means adapted to contact each of said conductive means, mounting means movably supporting said first contact means and both of said conductive means for relative movement toward and away from said second or said third contact means and said grounded means, and control means operatively associated with said first contact means and said conductive means to selectively move them in one direction relative to said second contact means and said grounded means to bring said first contact means into contact with said first conductive means and to move the latter away from said grounded means into contact with said second contact means, and simultaneously to separate said first contact means, said second conductive means, and said third contact means and permit said second conductive means to contact said grounded means, whereby said first conductive means acts as a connector between said first contact means and said second contact means when said control means is operated in said first direction and said second conductive means acts as an electrically grounded electro-static shield be-

tween said first contact means and said third contact means.

9. A shielded switching device, comprising, in combination, first contact means, second contact means, third contact means positioned on the opposite side of said first contact means from said second contact means, first conductive means interposed between said first and said second contact means, second conductive means interposed between said first and said third contact means, electrically grounded means adapted to contact each of said conductive means, mounting means movably supporting said first contact means and both of said conductive means for relative movement toward and away from said second or said third contact means and said grounded means, and control means operatively associated with said first contact means and said conductive means to selectively move them in one direction relative said second contact means and said grounded means to bring said first contact means into contact with said first conductive means and to move the latter away from said grounded means into contact with said second contact means, and simultaneously to separate said first contact means, said second conductive means, and said third contact means and permit said second conductive means to contact said grounded means, whereby said first conductive means acts as a connector between said first contact means and said second contact means when said control means is operated in said first direction and said second conductive means acts as an electrically grounded electro-static shield between said first contact means and said third contact means and shielding means surrounding all of said contact means and connected to said grounded means.

10. A shielded switching device, comprising, in combination, a first leaf spring carrying a first contact point, a second leaf spring carrying a second contact point, a third leaf spring carrying a third contact point, a first conductive member in the form of a fourth leaf spring interposed between said first and said second springs and normally positioned out of contact therewith, a second conductive member in the form of a fifth leaf spring interposed between said first and said third springs and normally positioned out of contact therewith, a sixth leaf spring carrying an electrically grounded contact point interposed between said first spring and said first conductive member and normally biased to contact the latter, a seventh leaf spring carrying an electrically grounded contact point interposed between said first and said second conductive member and normally biased to contact the latter, insulated mounting means movably supporting said springs in parallel relationship, and control means operatively connected to said first leaf spring selectively to move said first contact point in one direction into contact with said first conductive member to pick up the latter and move it away from its corresponding grounded contact point into contact with said second contact point, and simultaneously to permit said first contact point, said second conductive member, and said third contact point to separate and to form a connection between said second conductive member and its corresponding grounded contact point, whereby said first conductive member acts as a connector between said first contact point and said second contact point when said control means is operated in said first direction and said second conductive means acts as an electrically grounded

75 electro-static shield between said leaf spring and said third contact point.

11. A shielded switching arrangement, comprising, in combination, a first leaf spring carrying a first contact point, a second leaf spring carrying a second contact point, a conductive member in the form of a third leaf spring interposed between said first and said second springs and normally positioned out of contact therewith, a fourth leaf spring carrying an electrically grounded contact point interposed between said first spring and said conductive member and normally biased to contact the latter, insulated mounting means movably supporting said springs in parallel relationship, control means operatively connected to said first leaf spring selectively to move said first contact point in one direction into contact with said conductive member to pick up the latter and move it away from said grounded contact point into contact with said second contact point, and in a second direction to permit said first contact point, said conductive member, and said second point contact to separate and to restore the connection between said conductive member and said grounded contact point, first terminal means connected to said first leaf spring and projecting from said mounting means at a first point, second terminal means connected to said second leaf spring and projecting from said mounting means at a second point, and third terminal means connected to said third leaf spring and projecting from said mounting means at a third point in between said first and second points, whereby said third terminal means acts as an effective electro-static shield between said first and second terminal means when said control means is operated in said second direction.

12. A shielded switching device, comprising, in combination, a first leaf spring carrying a first contact point, a second leaf spring carrying a second contact point, a third leaf spring carrying a third contact point, a first conductive member in the form of a fourth leaf spring interposed between said first and said second springs and normally positioned out of contact therewith, a second conductive member in the form of a fifth leaf spring interposed between said first and said third springs and normally positioned out of contact therewith, a sixth leaf spring carrying an electrically grounded contact point interposed between said first spring and said first conductive member and normally biased to contact the latter, a seventh leaf spring carrying an electrically grounded contact point interposed between said first and said second conductive member and normally biased to contact the latter, insulated mounting means movably supporting said springs in parallel relationship, control means operatively connected to said first leaf spring selectively to move said first contact point in one direction into contact with said first conductive member to pick up the latter and move it away from its corresponding grounded contact point into contact with said second contact point, and simultaneously to permit said first contact point, said second conductive member, and said third contact point to separate and to form a connection between said second conductive member and its corresponding grounded contact point, first terminal means connected to said first leaf spring and projecting from said mounting means at a first point, second terminal means connected to said second leaf spring and projecting from said mounting means at a second point, third ter-

inal means connected to said third leaf spring and projecting from said mounting means at a third point, fourth terminal means connected to said fourth leaf spring and projecting from said mounting means at a fourth point in between said first and second points, and fifth terminal means connected to said fifth leaf spring and projecting from said mounting means at a fifth point in between said first and third points, whereby, said fourth terminal means acts as an effective electro-static shield between said first and second terminal means when said control means is operated in said second direction, and said fifth terminal means acts as an effective electro-static shield between said first and said third terminal means when said control means is operated in said first direction.

13. A shielded switching device, comprising, in combination, a first leaf spring carrying a first contact point, a second leaf spring carrying a second contact point, a third leaf spring carrying a third contact point, a first conductive member in the form of a fourth leaf spring interposed between said first and said second springs and normally positioned out of contact therewith, a second conductive member in the form of a fifth leaf spring interposed between said first and said third springs and normally positioned out of contact therewith, a sixth leaf spring carrying an electrically grounded contact point interposed between said first spring and said first conductive member and normally biased to contact the latter, a seventh leaf spring carrying an electrically grounded contact point interposed between said first and said second conductive member and normally biased to contact the latter, insulated mounting means movably supporting said springs in parallel relationship, control means operatively connected to said first leaf spring selectively to

move said first contact point in one direction into contact with said first conductive member to pick up the latter and move it away from its corresponding grounded contact point into contact with said second contact point, and simultaneously to permit said first contact point, said second conductive member, and said third contact point to separate and to form a connection between said second conductive member and its corresponding grounded contact point, first terminal means connected to said first leaf spring and projecting from said mounting means at a first point, second terminal means connected to said second leaf spring and projecting from said mounting means at a second point, third terminal means connected to said third leaf spring and projecting from said mounting means at a third point, fourth terminal means connected to said fourth leaf spring and projecting from said mounting means at a fourth point in between said first and second points, fifth terminal means connected to said fifth leaf spring and projecting from said mounting means at a fifth point in between said first and third points, whereby, said fourth terminal means acts as an effective electro-static shield between said first and second terminal means when said control means is operated in said second direction, and said fifth terminal means acts as an effective electro-static shield between said first and said third terminal means when said control means is operated in said first direction, and conductive portions forming parts of said sixth and seventh leaf springs and projecting from the non-contacting ends of said springs between said second and third terminal means to form an effective electro-static shield therebetween.

ROGER C. CURTIS.

CERTIFICATE OF CORRECTION.

Patent No. 2,318,761.

May 11, 1943.

ROGER C. CURTIS.

It is hereby certified that error appears in the printed specification of the above numbered patent requiring correction as follows: Page 5, second column, line 1, claim 10, before the words "leaf spring" insert --first--; and that the said Letters Patent should be read with this correction therein in that the same may conform to the record of the case in the Patent Office.

Signed and sealed this 14th day of September, A. D. 1943.

Henry Van Arsdale,
Acting Commissioner of Patents.
